TOOL HEAD FOR A LAWN RAKE

Walter R. Hart, Columbus, Ohio, assignor to The Union
Fork and Hoe Company, Columbus, Ohio

Filed Feb. 24, 1970, Ser. No. 21,582

Term of patent 14 years

Int. Cl. D8—01

U.S. Cl. D8—13

FIG. 1 is a perspective view of a tool head for a lawn rake showing my new design;

FIG. 2 is a front elevational view; and

FIG. 3 is a side elevational view thereof.

The characteristic feature of my claimed tool head resides in the specific configuration of the tine elements as shown.

I claim:

The ornamental design for a tool head for a lawn rake, substantially as shown, and described.
